UNITED STATES PATENT OFFICE.

BENJAMIN B. BRYAN, JR., OF NEW YORK, N. Y.

MEANS FOR APPLYING TO USEFUL PURPOSES THE ENERGY DEVELOPED THROUGH THE MOMENTUM OF MOVING TRAINS.

Application filed July 9, 1926. Serial No. 121,300.

This invention relates to means for the utilization of power developed by moving bodies, such as trains travelling on rails, and my improvements, while not so limited, are directed 5 in one phase thereof to means for harnessing the energy represented by the momentum of a train descending a grade, together with means for applying that energy to the generation of electricity, for useful purposes.

10 Also my invention comprehends the employment of movable means located in the vicinity of stations or stopping places and adapted to function as braking or speed retardation means for a train while absorbing its 15 momentum for the generation of power applicable to other, useful purposes.

In railroading there exist many extensive track sections having a down grade upon which trains may travel largely under the 20 influence of gravity, the weight of the train furnishing momentum that is more than sufficient to maintain a desirable travel speed, and therefore my invention contemplates the capture and turning to useful account of the 25 surplus energy which today is lost by absorption into the braking systems in vogue.

Therefore my invention consists in paralleling the track with an endless belt, suitably mounted and adapted to operate one or more 30 electrical generators, the belt being provided with engaging means adapted to co-act with a projection from a train on the track, so that the belt will be given continuous movement while the train is travelling over the section of 35 track equipped in the manner set forth.

Realizing that breakage would result if the engaging means on the belt, while stationary, were struck by a train travelling at fast or even moderate speed, I have provided independent means for setting in motion the power 40 generating belt and according it a speed approximating the speed of the oncoming train, to the end that the engaging means respectively on the train and belt may connect without shock or sudden impact.

Further my invention includes the provision of means whereby the independent belt operating means may be energized automatically as the train approaches a track section 45 equipped with my new power generating means, and again de-energized when the train picks up the load.

The braking effect upon a train resulting from the use of the power generating belt 50 can be advantageously employed at all stop-

ping places, whether on grades or on level stretches, and this feature will be of particular value for subways, where great waste in energy occurs with the braked stoppages at numerous stations. 60

Other features and advantages of my invention will hereinafter appear.

In the drawings:

Figure 1 is a diagrammatic view, in plan, of a track-way, a train represented by a locomotive thereon, power generating means for operation by the train, and automatic initially actuating means for the power generator. 65

Fig. 2 is a side elevation of Fig. 1.

Fig. 3 is a more extended, side view of the 70 generating means showing a long freight train as the actuator thereof.

Fig. 4 is a plan view of a track-way, with a power generating belt alongside, showing a 75 number of generators operable by said belt.

Fig. 5 is a side elevation showing a locomotive, a generator, a belt and interengaging means respectively on said locomotive and belt.

Fig. 6 is a transverse section of the endless 80 belt, with one of its revolute mounts and carrying a fixed detent, and

Fig. 7 is a plan view typical of an installation 85 of my system for subways or elevated railways wherein the frequent train stoppages enable the conversion of my improved braking means into power generation.

In the drawings let 1 indicate a railway track, including a section 2 that is insulated from the main part of the track by insulation such as is indicated at 3, 3. This section 2, which is of a desirable length, is included in an electrical circuit 4 having a source of electrical energy 5, the circuit 4 also including an electro-magnet 6 that attracts an armature 7 to thereby hold open another circuit 8, which other circuit 8 has a source of electrical energy 9 and, when closed, serves to operate a motor 10. But the circuit 4, being normally closed, thereby causes motor 10 to be normally inactive. 90

As has been premised one of the objects of my invention is to enable a train in motion to generate electrical current for general power uses, for which purpose I cause the track, or a portion thereof, and particularly a down grade portion, to be paralleled with a belt 11, which may be mounted on revolute supports 12, said supports having suitable rotative means, such for example as the shafts 13, for 105 110

the operation of electrical generators 14, these generators being disposed suitably alongside the track in places where they will serve conveniently as power producers. 5 Therefore the belt 11 carries a number of projections or detents 15, which are secured thereto and caused to extend from the belt in manner to lie in the path of a spur or dog 16 which extends for that purpose from the 10 train. As here shown this dog is pivotally connected at 17 to the locomotive 18, said dog being adapted to swing or be swung forwardly, so that it may not engage with the belt when the train is moving in the rearward 15 direction, but a fixed stop 19 or equivalent means upon the locomotive preventing said dog from having independent rearward motion, whereby said dog, when the train is moving forwardly, will engage one of the detents 15 and thereby communicate the train 20 movement to the belt.

Realizing that if a train moving at even moderate speed should cause its dog 16 to strike a detent on the belt while said belt 25 was stationary the momentum of impact would cause breakage of the engaging members, or one of them, to result, I have provided auxiliary power means, automatically set in operation for establishing movement 30 of the belt 11, approximating the travel speed of the train, just prior to the entry of the train upon the track portion equipped with belt 11, so that the dog 16 may come into engagement with a detent on the belt 35 substantially without shock, whereupon, according to my invention, said auxiliary power means will cease to function.

As an example of means for automatically applying and disconnecting auxiliary power 40 means for establishing motion in the belt 11, I have shown the belt 20 which connects one of the revoluble supports 12 for belt 11 with a shaft 21 that extends from and is actuated by motor 10.

45 As has previously been stated, the circuit 8 is normally open, but when the locomotive or train 18 enters upon the insulated track section 2, thereby a short circuit is effected in the circuit 4, the current passing through 50 the wheels and axle of the locomotive, thus de-energizing magnet 6, and allowing circuit 8 to close for the operation of motor 10.

The insulated track section 2 will be of sufficient length to permit belt 11 to attain a 55 desired speed before the last car of the train leaves said section, by which time the dog 16 will have engaged one of the detents 15, and thereafter the travel movement of the train will move the belt 11 for the operation 60 of all the generators actuatable thereby. Also, as soon as the train leaves track section 2 circuit 4 will again energize magnet 6 and cause circuit 8 to open.

In Fig. 3 I have shown the track 1 as a 65 down grade, and a lengthy freight train

thereon, the rear car as well as the locomotive being provided with a dog 16 for engaging a detent 15 on belt 11, in order that the power transmission to the belt may be continued thereby until the entire train passes 70 beyond the belt.

It will of course be understood that I set no limit to the length of belt 11 as its extent will be suited to the conditions of service.

In Fig. 7 there appears an example of an 75 urban, or suburban railway track 22, such as is provided with a succession of stations 23 that are relatively closely spaced, involving frequent stoppings of the trains. It is my purpose with these systems of traction to effect 80 an exchange of power between the train momentum—as applied to the generation of electricity for useful purposes—and the force that is needful to brake the speed of the train so that it may come to a stop at the station 85 platform.

For these purposes a similar arrangement may be provided to that already described, namely, the insulated track section 31, having circuit 24 to energize magnet 25, the train 26 90 to short circuit the circuit 24, thereby closing circuit 27, and the power transmission belt 28 actuating generators 29, together with the starting up belt 30 operated by circuit 27 when the train is on track section 31, said belt 95 30 ceasing to function when the train leaves said section.

In this application of my invention it is 100 equally necessary to impart to belt 28 a speed of movement approximately that of an on-coming train before the train enters the zone or station in which the braking operation is 105 to be performed. It is customary for these urban and suburban trains to run at high speed right into the stations and to be brought 110 to a stand-still through powerful brakes while moving along the lengthy platform. Therefore I arrange the belt 28, suitably guarded, alongside the platform, or it may be under the platform, in position for engagement by 115 trains entering the station, that it may serve both as speed retardation and braking means for the trains, and to transmit the momentum of the trains to the generators 29.

While in the foregoing description I have 120 referred to the bodies movable upon a track as a train I do not wish to be limited thereby to a number of cars and locomotive coupled together, but the term "train", both in the description and in the appended claims, is intended to designate any rolling stock movable upon a track, such as a single car, a locomotive, or any number of cars or cars and locomotive coupled together.

Variations within the spirit and scope of 125 my invention are equally comprehended by the foregoing disclosure.

I claim:

1. The combination with a railway and a 130 train movable thereon, of an electrical gener-

ator located adjacent a section of said railway, transmission means extended along said section and movable with the train, means actuatable by an approaching train to set said 5 transmission means in motion, and co-acting means between said train and transmission means for the operation of said generator by the train momentum.

2. The combination with a railway and a 10 train movable thereon, of an electrical power generator located adjacent a section of said

railway, movable braking means located along said section, means actuatable by an approaching train to set said braking means in 15 motion, said power generator actuatable by said braking means, and engaging means between said train and braking means for retarding the speed of the train while transmitting its momentum for the operation of 20 the generator.

Executed this 14th day of June, 1926.

BENJAMIN B. BRYAN, JR.
